UNITED STATES PATENT OFFICE.

HENRY S. GERMOND, JR., OF BAYONNE, NEW JERSEY.

ELEVATING APPARATUS.

Application filed October 6, 1927. Serial No. 224,378.

This invention relates in general to elevating apparatus and particularly to portable elevators or so-called tiering machines which comprise a portable vertical frame upon which is vertically movable by hoisting apparatus a load carrying platform. The hoisting apparatus now is usually driven by electric motors, and either mechanical or solenoid brakes are commonly utilized for holding the platform in elevated position. Also means is usually provided for simultaneously automatically shutting off the power, such as electric current, from the hoisting apparatus and automatically applying the brake when the platform reaches its upper limit and its lower limit of movement, such means comprising a control chain or cable running freely over pulleys at the top and the bottom of the elevator frame and having stop blocks engaged by a projecting stop arm on the platform, and means connecting the cable to the power control means and the brake so that movement of the cable caused by contact of said stop arm with either stop block shuts off the power and applies the brake. With such constructions now known considerable difficulty is experienced by presence of slack in the cable or chain and lost motion thereof over the pulleys, which makes the operation of the power control means and the brake mechanism slow and unreliable, and the slack chain or cable is an obstruction or hindrance to other moving parts.

One object of my invention is to provide elevating apparatus of this general character including novel and improved means for maintaining the cable or chain taut to eliminate lost motion, and to provide a positive and quick acting connection of the cable or chain to the power control means.

Another object is to provide a novel and improved construction whereby both the brake and the power control means, such as an electric switch, are operated instantly, positively, and simultaneously upon movement of the control cable.

A further object is to provide in such apparatus a novel and improved combination of means for maintaining the control cable taut and eliminating slack and relative sliding of the cable and the pulleys, and means for operating the brake and the power control means, whereby power to operate the brake and the power control means is applied to the brake and the power control means from the same point both in manual operation and through

the control cable, so that direct, positive and quick operation of both the brake and the power control means is ensured at all times whether the controlling movement is applied to the control cable by an operator on the platform or on the floor, or is automatically applied by the platform.

Other objects are to provide apparatus of this character wherein the control cable is wound around a drum on the brake shaft which is connected by crank arms and a link to the shaft of the power controlling means, and the brake shaft has an operating handle for manual control, whereby said drum serves both to maintain the control cable taut and to operatively connect the cable to the brake shaft; to provide such a construction including a minimum number of simple and inexpensive parts, and to obtain other advantages and results as may be brought out by the following description.

Referring to the accompanying drawings in which corresponding and like parts are designated throughout the several views by the same reference characters,

Figure 1 is a side elevation of a portable elevator embodying my invention, certain details of construction of elevators not essential to an understanding of the invention being omitted;

Figure 2 is a front elevation of the elevator, and

Figure 3 is an enlarged fragmentary end view of the brake mechanism.

Specifically describing the illustrated embodiment of the invention, the elevator is of the general type described in United States Patent No. 1,197,597, dated September 12, 1916, and comprises a vertical frame A formed of two upright and spaced channel bars which have their channels facing each other. A load carrying platform B is mounted on rollers C within the channels of the bars 1 to move up and down on the frame A. Any suitable mechanism may be utilized for raising and lowering the platform, but in the present instance I have shown this mechanism as comprising a cable 2 to pass over a sheave 3 mounted at the upper end of the frame, the cable being attached to a drum 4 mounted on a supplementary frame 5. The drum is driven through a gear 6 meshed with a pinion 7 on a countershaft 8 upon which is also mounted a gear 9 which meshes with another pinion 10 on a second countershaft 11. The countershaft 11 also has mounted thereon a

sprocket 12 connected by a chain 13 to a sprocket 14 on the shaft of a reversible motor 15. With this construction, obviously rotation of the motor in opposite directions will cause respective raising and lowering of the platform B.

The motor 15 is controlled by an electric switch 16 of known construction which includes a shaft 17 having a crank arm 18 thereon. The switch is in neutral or open position when the crank arm is substantially horizontal, and is closed to start the motor in one direction when the arm 18 is swung upwardly and closed to start the motor in the other direction when said arm is swung downwardly.

Brake mechanism D is provided for holding the platform B in any position on the frame A. The brake mechanism is identical with that disclosed in said Patent No. 1,197,597 and includes brake drum 19 rotatable on the countershaft 11, the drum having an interior ratchet 20 with which cooperates a spring pawl 21 carried by a cross head 22 fixed upon the shaft 11. A pair of brake shoes 23 surround the brake drum and are connected at one end by a tiebolt 24. The ends of the shoes are bifurcated and embrace an operating shaft 25, a compression spring 26 being arranged on said shaft to normally force said brake shoes out of engagement with the drum. For forcing the brake shoes into engagement with the drum a pair of cams 27 are keyed on the shaft 25 and cooperate with the follower rollers 28 on the respective brake shoes. With this construction when the shaft 25 is rotated in one direction the cams 27 are rotated so as to permit the brake shoes to be disengaged from the drum by the spring 26, while when the shaft 25 is rotated in the other direction the brake shoes are forced by the cams 27 tightly into engagement with the drum to prevent rotation thereof. It will be observed that the operating shaft 25 in connection with the brake drum permits free rotation of the shaft 11 to elevate the platform, but backward rotation of the shaft in a direction to permit descent of the platform is prevented until the brake shoes are positively released by rotation of the shaft 25.

A drum 30 is fixed upon the shaft 25 and has wound around it a control cable 31 which also passes freely around pulleys 32 at the upper and lower ends of the frame A. Turnbuckles 33 may be provided for adjustment of the cable on the respective pulleys and the drum. Upon the reach of the cable 31 opposite that wound around the drum 30 are fixed stop blocks 34 to be engaged by a stop arm 35 on the platform B, one stop block being arranged at the upper limit of movement of the platform and the other stop being arranged at the lower limit of movement. The drum is preferably provided with a handle

36 whereby the shaft 25 may be rotated by an operator standing on the floor.

Shaft 25 is also provided with a crank arm 37 which is connected by a link 38 to the crank arm 18 on the switch shaft 17, so that rotation of the shaft 25 will cause simultaneously rotation of the shaft 17.

With this construction, it will be observed that the cable 31 will be moved by engagement of the stop arm 35 with the stops 34 and will rotate shaft 25 through the drum 30 in one direction or the other. The parts are so arranged and connected that when the shaft 25 is in the position indicated by the handle 36 illustrated in solid lines, the circuit through the switch 15 is open and the brake mechanism is applied or set. When the handle 36 is swung upwardly the brake is released and the circuit through the switch 16 is closed so that the motor 15 rotates the drum 4 to raise the platform; while when the handle is moved downwardly the brake is released and the circuit through the switch 16 is closed to cause the motor 15 to rotate the drum to lower the platform. Obviously, when the platform reaches the lower limit of its movement the cable 31 will be moved by the stop arm 35 so as to rotate the brake shaft 25 and the switch shaft 17 simultaneously into neutral position so that the brakes are automatically applied and the switch simultaneously automatically opened. Similar action takes place when the platform reaches the upper limit of its movement, the handle 36 being swung downwardly into said neutral position.

It will be observed that the drum 30 serves both to maintain the cable taut and to prevent any lost motion between the cable and the pulleys 32, and also to positively connect the cable to the brake shaft. Furthermore it will be observed that the power for operating the brake and the switch is applied at the same point, that is the drum 30, whether the actuation is automatic by the platform, or by an operator on the platform grasping the cable, or by an operator on the floor grasping the handle 36. Direct, positive, quick and simultaneous actuation of the brake and the switch is accordingly ensured at all times, and there are a minimum number of simple parts so that there is little danger of failure of operation and the apparatus will be long lived and reliable even in the hands of an unskilled person. The connection of the cable 31 to the shaft 25 through the drum 30 is such that there is no bending or flexing of the reaches of the cable as is the case where the cable is connected to a lever, and this permits the cable to be maintained taut which is not possible where some play or flexibility in the cable is required as with a lever.

It should be understood that while I have illustrated one specific embodiment of my invention this is primarily for the purpose of illustrating the principle of the invention,

and many modifications and changes by those skilled in the art without departing from the spirit or scope of the invention may be made. For example, a segment of the drum might be used with the upper and lower ends of the cable connected to the lower and upper ends of the segment, respectively, so that the cable is always in lines tangent to both the segment and the pulleys 32. Therefore, I do not desire to be understood as limiting myself except as required by the following claims when construed in the light of the prior art.

Having thus described the invention, what I claim is:

1. Elevating apparatus comprising a frame, a load-carrying platform mounted to move thereon, power-driven means for moving said platform, brake mechanism for controlling said power-driven means, power-controlling means for regulating the application of power to said power-driven means, a shaft, a drum fast mounted on said shaft, a cable movable on said frame and wound around said drum so that movement of said cable rotates said drum, cooperating means on said platform and said cable so that the cable will be moved by said platform at certain points in the movement of said platform in opposite directions, an operative connection between said shaft and said brake mechanism, and an operative connection between said shaft and said power-controlling means, whereby said drum may be rotated by said cable to apply and release said brake mechanism and actuate said power-controlling means to regulate the power supplied to said power-driven means.

2. Elevating apparatus comprising a frame, a load-carrying platform mounted to move thereon, power-driven means for moving said platform, brake mechanism for controlling said power-driven means, power-controlling means for regulating the application of power to said power-driven means, a shaft, a drum fast mounted on said shaft, spaced pulleys on said frame, an endless cable mounted on said pulleys and having one reach wound around said drum so that movement of said cable rotates said drum, an operative connection between said shaft and said brake mechanism and an operative connection between said shaft and said power-controlling means, whereby said drum may be rotated by said cable to apply and release said brake mechanism and actuate said power-controlling means to regulate the power supplied to said power-driven means.

3. Elevating apparatus comprising a frame, a load-carrying platform mounted to move thereon, power-driven means for moving said platform, brake mechanism for controlling said power-driven means, power-controlling means for regulating the application of power to said power-driven means and in-

cluding a rotatable operating shaft, a crank arm on said shaft, a second rotatable shaft, an operative connection between said second shaft and said brake mechanism, a cable mounted to move on said frame, means connecting said cable to said second shaft so that movement of said cable rotates said second shaft to apply and release said brake mechanism, a crank arm on said second shaft, a link connecting said crank arm on said second shaft to said crank arm on the first-mentioned shaft so that movement of said cable causes application and release of said brake mechanism and respectively simultaneously therewith the shutting off and application of power from and to said power-driven mechanism, and cooperating means on said platform and said cable so that said platform moves said cable at certain points in the movement of said platform.

4. Elevating apparatus comprising a frame, a load-carrying platform mounted to move thereon, power-driven means for moving said platform, brake mechanism for controlling said power-driven means, power-controlling means for regulating the application of power to said power-driven means and including a rotatable operating shaft, a crank arm on said shaft, a second rotatable shaft, an operative connection between said second shaft and said brake mechanism, a drum fast on said second shaft, a cable movable on said frame with an intermediate portion wound around said drum so that said cable is operatively connected to said drum and movement of said cable rotates said drum and said drum maintains said cable taut, a crank arm on said second shaft, a link connecting said crank arm on said second shaft to said crank arm on the first-mentioned shaft so that movement of said cable causes application and release of said brake mechanism and respectively simultaneously therewith the shutting off and application of power from and to said power driven mechanism, and cooperating means on said platform and said cable so that said platform moves said cable at certain points in the movement of said platform.

5. Elevating apparatus comprising a frame, a load-carrying platform mounted to move thereon, power-driven means for moving said platform, power-controlling means for regulating the application of power to said power-driven means, a shaft, a drum fast mounted on said shaft, a cable movable on said frame and wound around said drum so that movement of said cable rotates said drum, cooperating means on said platform and said cable so that the cable will be moved by said platform at certain points in the movement of said platform in opposite directions, and an operative connection between said shaft and said power-controlling means, whereby said drum may be rotated by said

cable to actuate said power-controlling means to regulate the power supplied to said power-driven means.

6. Elevating apparatus comprising a frame, a load-carrying platform mounted to move thereon, power-driven means for moving said platform, power-controlling means for regulating the application of power to said power-driven means, a shaft, pulleys on said frame, a cable movable over said pulleys, means connecting said cable to said shaft so that said cable is always in lines tangent to both said pulleys and an arc con-

centric with said shaft and so that movement of said cable rotates said shaft, cooperating means on said platform and said cable so that the cable will be moved by said platform at certain points in the movement of said platform in opposite directions, and an operative connection between said shaft and said power-controlling means, whereby said drum may be rotated by said cable to actuate said power-controlling means to regulate the power supplied to said power-driven means. 15 20

HENRY S. GERMOND, JR.
